UNITED STATES PATENT OFFICE.

HARRY H. SCHROYER, OF CHICAGO, ILLINOIS, ASSIGNOR, BY DIRECT AND MESNE ASSIGNMENTS, TO HIMSELF, JAMES H. DONALDSON, AND E. J. WARD COMPANY, OF CHICAGO, ILLINOIS, A CORPORATION OF ILLINOIS.

DIAPHRAGM FOR CAR-VESTIBULES OR THE LIKE.

SPECIFICATION forming part of Letters Patent No. 710,924, dated October 7, 1902.

Application filed April 20, 1901. Serial No. 56,794. (No model.)

To all whom it may concern:

Be it known that I, HARRY H. SCHROYER, a citizen of the United States, and a resident of Chicago, in the county of Cook and State 5 of Illinois, have invented certain new and useful Improvements in Diaphragms for Car-Vestibules or the Like; and I do hereby declare that the following is a full, clear, and exact description thereof, reference being had to 10 the accompanying drawings, and to the letters of reference marked thereon, which form a part of this specification.

This invention relates to improvements in diaphragms for car-vestibules or the like. 15 Heretofore in devices of this class the material of which the diaphragm is constructed has been folded in accordion-plaits and secured by its edges to the car and to the diaphragm face-plate. Owing to the same being under almost 20 constant tension, subjected to constant vibration and the action of atmospheric moisture and gases, the same, if of rubber, is short-lived, frequently breaking adjacent to the bend or fold. Cinders or sparks falling on 25 top of the flexible hood or canopy commonly used burn holes therethrough and permit dirt and moisture to find lodgment in the angles in the top of the diaphragm. The object of this invention is to provide a construction 30 of great strength and durability readily attached to the car and face-plate and provided with means for preventing dirt or moisture finding its way into the angles between the plaits. A construction embodying my invention while more pleasing to the eye is at the 35 same time much cheaper and far more durable.

The invention consists of the matters hereinafter described, and more fully pointed out 40 and defined in the appended claims.

In the drawings, Figure 1 is a fragmentary vertical section of a device embodying my invention. Fig. 2 is a section taken on line 22 of Fig. 1. Fig. 3 is an enlarged detail illustrating 45 the manner of attaching the auxiliary hood. Fig. 4 is a fragmentary perspective view.

As shown in said drawings, said diaphragm is constructed of a plurality of strips A, of fabric, such as cotton-beltng or other suitable material, of a width approximately equal

to the width of the diaphragm-folds and of a length and form sufficient that each strip extends across the top and down each side of the complete diaphragm. A sufficient number of said strips are imposed one upon the other, and the corresponding edges of adjacent strips are rigidly secured together in pairs by means of rivets or the like, thereby forming a plurality of accordion-plaits, which when opened present the appearance as indicated in Figs. 2 and 4.

For the purpose of affording a desirable finish and also to prevent cinders, dirt, or moisture finding lodgment between the strips a fold of material (indicated by a) is secured 65 to cover the meeting edges, and the rivets wherewith the same are secured together pass therethrough, as indicated in Fig. 3. Obviously said covering may be of any desired material, such as leather or waterproof fabric. 70 Preferably, however, a metallic band bent to suitable form is secured on said angles, as before described.

Usually in constructions of the class described a hood of flexible waterproof material (shown in dotted lines in Fig. 2) is secured on the vestibule-hood and on the diaphragm face-plate B for the purpose of shedding dirt, atmospheric moisture, and dust, sparks, or cinders from the diaphragm. 75 Said material usually soon becomes apertured by sparks and cinders falling thereon and fails to perform its office. As a further improvement I have provided supplemental hoods C in each fold at the top of the diaphragm. The outer ends of said auxiliary or supplemental hoods incline downwardly and beyond the inner meeting edges of the strips A 80 at each side of the diaphragm, as indicated in Figs. 1 and 4, and the edges thereof are 85 permanently secured at the top of the diaphragm within the channels or coverings C and secured therein and to the upper edges of the strips A by the rivets a', as indicated in Figs. 2 and 3. Said auxiliary hoods are 90 preferably much thinner than the strips A of which the diaphragm proper is composed and may be constructed of any desired water and fire proof material, such as prepared canvas, 95 coated rubber fabric, or the like.

Obviously from the construction described while the flexible hood ordinarily used with diaphragms of the class described may be dispensed with the same will preferably be retained as heretofore, in which case the auxiliary hood acts to catch all moisture, dirt, or refuse finding its way through said hood and owing to its inclination discharges the same therefrom clear of the diaphragm.

Obviously diaphragms embodying my invention may be constructed, if preferred, of soft-steel plates or sheets of other metal and whatever the material may be very quickly applied to a car by riveting or bolting the edges at each end thereof to the face-plates, in which instance said edges may be covered with an angle-strip of metal *c*, rigidly secured on the face-plate and diaphragm by means of rivets or bolts which pass therethrough and act to bind the same rigidly together.

Obviously many features of construction may be varied without departing from the principle of my invention.

I claim as my invention—

1. A diaphragm comprising a plurality of strips of fabric placed one upon the other, the opposite edges of each strip being permanently secured in pairs to the edges of the adjacent strips and a reinforcing-cover of metal on each outer seam secured thereto by rivets passing through said covering and through both strips.

2. As an article of manufacture a diaphragm comprising a plurality of strips of fabric superposed and having the opposite

edges united in pairs with adjacent strips and a longitudinal stay comprising a channel of metal reinforcing the same at said meeting edges of said strips and covering the angle thereof rigidly secured thereto by rivets 40 or like means.

3. A car-vestibule diaphragm constructed of a plurality of superposed strips each adapted to extend along the top and sides of the vestibule, a reinforcing-strip engaging and 45 covering the corresponding edges of adjacent strips and secured thereon by means of rivets or the like and an auxiliary hood secured at the top between adjacent strips and having its edges secured beneath said cover or reinforcing-strip.

4. In a diaphragm for car-vestibules, the combination with a plurality of strips superposed and adapted to extend across the top and down each side of the vestibule and having the opposite edges secured together in pairs with an adjacent strip, of an auxiliary hood secured across the top of the diaphragm between adjacent strips and having its edges secured at the upper meeting edges thereof, 55 the ends of said auxiliary hood being downwardly inclined and extending beyond the inner meeting edges of the strips.

In testimony whereof I have hereunto subscribed my name in the presence of two sub- 65 scribing witnesses.

HARRY H. SCHROYER.
